By his Attorney JAMES MARTIN,

Geo. W. Misch

UNITED STATES PATENT OFFICE.

JAMES MARTIN, OF NEW YORK, N. Y.

DESIGN FOR A PNEUMATIC TIRE SHOE OR TREAD.

54,434.

Specification for Design.

Patented Feb. 10, 1920.

Application filed August 21, 1919. Serial No. 319,028. Term of patent 3½ years.

To all whom it may concern:

Be it known that I, JAMES MARTIN, a citizen of the United States, residing at the borough of Manhattan, city, county, and State of New York, have invented a new, original, and ornamental Design for Pneumatic Tire Shoes or Treads, of which the following is a specification, reference being had to the accompanying drawing, forming a part thereof.

Figure 1 is a flat elevation of a portion of

the periphery of a pneumatic tire tread, showing my new design; and Fig. 2, a transverse section taken upon plane of line $x-x$, Fig. 1.

I claim:

The ornamental design for a pneumatic tire shoe or tread, as shown.

JAMES MARTIN.
